PREFABRICATED STEP UNIT

Smith Alonzo Rosenberger, Valparaiso, Ind.

Application July 20, 1938, Serial No. 220,275

3 Claims. (Cl. 72—96)

My invention relates to improvements in prefabricated step units and the forms therefor and it more especially consists of the features pointed out in the claims.

5 The purpose of my invention is to prefabricate and standardize the required parts of step structures so that stringers of predetermined lengths with fastening bolts embedded therein, and corresponding lengths of risers and the required length of treads may be made up of cement or any other material and stocked for future sale; that may utilize cooperating forms in which to "cast" the members so that the same form with exchangeable end blocks will serve 10 both for the risers and stringers; that may use another form with adjustable ends for the treads; and that optionally may use standard sized angle plates for tying the stringers to the risers; and that also provides a templet for determining the location of the fastening bolts in the stringers and the risers.

A further advantage of my invention lies in the simplicity of assembling the parts so that an unskilled person can complete a step of a desired number of treads. After the risers and stringers are assembled on a suitable concrete-cement foundation, the treads without any fastenings rest on the stringers and risers.

With these and other ends in view I illustrate 30 in the accompanying drawing such instances of adaptation as will disclose the broad invention without limiting myself to the specific details shown thereon and described herein.

Fig. 1 is a fractional front view with parts removed.

Fig. 2 is a side elevation with the nearest stringers removed to show the underneath structure.

Fig. 3 is a top plan view with parts removed.

40 In practicing my invention I may use whatever equivalences and adaptations of structure that the exigencies of varying conditions may demand without departing from the broad features of the invention.

45 The component parts of the structure will be first described. A prefabricated step includes as many treads 1 as there are risers 2 and there are twice as many stringers 3 of varying length as there are risers and treads. Should a step of extra width be desired a pair of stringers will be placed at the center, lengthwise of the step (not shown) and of course a stringer at each end. Each tread at the center will be shortened the amount of the usual overhang so that the two treads will abut each other lightly. The pair of

central stringers may be bolted to each other in any desirable manner.

The risers 2 and the stringers 3 are held in engagement with each other by means of bolts 4 "cast" into the cement. Angle plates 5 fit into the adjacent corners and pass over the bolts 4 where they are held by nuts 6. At the rear end of the stringers 3 the shortest one 7 at the top and the longest 8 at the bottom are held against vertical displacement by angle bars 9 that are secured to the stringers by "cast in" bolts 4. At the top, an angle plate 5 is placed against the stringer and the angle bar 9 against the plate 5. The bar lies against all the stringers occurring successively below the top one. Bolts 4 hold it to each stringer, a duplicate angle bar is placed inside the other group of stringers in the same way and in case a pair of stringers are used in the center of a long step a bar 9 is placed alongside of each group of stringers. In such an event long trough bolts would be used instead of the "cast in" bolts 4. Similarly the angle plates 5 on opposite sides of a pair of stringers would be held by trough bolts long enough to pass through both sets of stringers.

25 The stringers 3 have beveled front ends 13, and the risers 2 are similarly beveled at 14. The treads 1 are held in place by their own weight. The underside projection 15 at its front edge abuts risers 2 and the ends of the projection 15 hold the treads against endwise movement because the projection drops below the top face of the adjacent riser and stringers. It is obvious that my preformed step may, if desired, be assembled without the use of any fastening 30 means, due to the weight of the treads.

25 An advantageous feature of the complete step made up in accordance with my invention will maintain its stability and assembled relation regardless of extremes of temperature. The bolts, 40 nuts, angle plates and angle bars if used may be galvanized or formed of rust-proof iron and if desired the angle plates may have the holes for the bolts either slightly elongated or of a slightly larger diameter to admit of adjustment in 45 assembling the step members or while in use. In addition any underside projection of the treads may have a certain tolerance of clearance at the front edge and the ends to allow for expansion, should such be found necessary.

50 What I claim is:

1. As a new article of manufacture, prefabricated component parts of a composition step which include a unitary tread portion, having an underside projection, a unitary riser member, 55

a plurality of cooperating stringers, and means for holding the parts in assembled relation with the under projection of the tread in approximate contact with the inside face of a riser and a pair of stringers to position the stringers in spaced apart relation.

2. A prefabricated tread member for assembly on interconnected stringers and risers, and an underside projection of the tread adapted to position it between a pair of stringers and to the rear of the riser whereby the tread is maintained in position by reason of its inherent weight.

3. In a unitary composition step, a plurality of stringers, completely beveled front ends thereon, a plurality of risers, partially beveled ends on the risers, means for assembling a riser and two stringers with their beveled ends adjacent each other, "cast in" bolts projecting from the inner faces of the stringers and the riser, angle plates provided with holes to receive the bolts, and nuts to hold the plates against the stringers and risers.
